LIQUID-DISTRIBUTUTING DEVICE

Fingal C. Orr, Glendale, Calif.

Application February 16, 1953, Serial No. 337,135

8 Claims. (Cl. 299—69)

This invention has to do with devices for distributing liquids in circular paths occupying a multiplicity of planes.

An object of my invention is to provide a novel, liquid-distributing device which is actuated by the liquid to cause the discharged liquid to move in circular paths occupying different planes.

More particularly it is an object to provide a sprinkler or liquid discharge device in which a single nozzle or discharge tube is mounted for rotation about two mutually perpendicular axes and is effective to accomplish rotation of the nozzle about both such axes.

Another object is to provide a device which is of simple construction, can be easily fabricated, and has a variety of uses.

These and other objects will be apparent from the drawing and the following description. Referring to the drawing:

Fig. 1 is an elevational view of a device embodying the invention;

Fig. 2 is a plan view of the device of Fig. 1;

Fig. 3 is a sectional view on line 3—3 of Fig. 1;

Fig. 4 is a fragmentary elevational view on line 4—4 of Fig. 2;

Fig. 5 is a fragmentary elevational view of a modified pawl mechanism; and

Fig. 6 is a fragmentary elevational view on line 6—6 of Fig. 5.

More particularly describing the invention, 11 generally indicates an X-shaped fitting member having a depending central neck 12 internally threaded at 13 to receive a tube 14. The latter is slidably and rotatably mounted within a main fitting 16 in the form of a tubular body terminating at its lower end in a threaded portion 17 for attachment to a supply pipe 18. Tube 14 extends through fitting 16 and is fitted with a collar 20 at its lower end to limit upward movement of the tube.

The member 11 rotatably supports a horizontal tubular shaft 22 which is closed at one end as by plug 23. The shaft is apertured at 22' within fitting 11 so that it will receive fluid delivered by tube 14. At its other end there is rigidly mounted a spray head or discharge head assembly, generally indicated by 24, and including a head 25 having a neck 26 attached rigidly to the shaft 22 and having a portion 27 at right angles thereto fitted with a discharge tube or nozzle 28. The member 25 also carries an actuator member 30 which is mounted on a pin 32 which is rotatably mounted in the fitting 25. The actuator member is attached at one end of the pin. The other end of the pin is apertured at 33 to receive coil spring 34, one end of which is anchored in an apertured abutment lug 35 on the body 25. The spring serves to bias the actuator member toward and against the lug 35.

The actuator member includes a spoon-shaped deflector end portion 38 normally in the path of liquid emerging from nozzle 28 and a laterally disposed vane 39.

The fitting 11 is provided with a laterally projecting pin 41 which is threaded into the body. Pivotal mount-

2

ed on this is a pawl 42 which hangs by gravity in an inclined position. The lower end of the pawl rests against a serrated track 44 of circular shape formed on the upper surface of a flange 45 mounted on the fitting

5 16. The pawl prevents rotation of fitting 11 and carried parts in a counterclockwise direction as viewed in Fig. 2.

In the operation of the device liquid delivered by the supply pipe 18 passes through tube 14 to the interior of fitting 11 and then enters shaft 22 flowing to fitting 25

10 and emerging at a relatively high velocity through the nozzle 28. The emerging liquid impinges upon the deflector portion 38 of the actuator member, causing this member to pivot to the left, as the device is viewed in

15 Fig. 2. In so pivoting, the vane 39 enters and passes through the fluid stream serving to carry the actuator member to a position such that it occupies substantially the broken-line position shown in Fig. 2. Spring 34

returns the actuator member to the original position. As a result of the forces involved, the head 25 and shaft

20 22 rotate about the axis of shaft 22 and at the same time the assembly carried by tube 14 is caused to rotate about the axis of tube 14 intermittently due to the reactionary force of liquid issuing from the nozzle when the parts are

25 in the position shown in Fig. 2. Any tendency of the discharging fluid to reverse this direction of rotation of the entire assembly carried by the member 11 is prevented by pawl 42 which permits rotation of the aforementioned assembly clockwise as viewed in Fig. 2 but prevents rotation in the opposite direction.

While the pawl 42 will operate under the influence

of gravity alone I may provide a spring to urge it toward the flange 45. Thus in Figs. 5 and 6 I show a pawl 42a

35 carried on an elongated pin 41a which accommodates a coil spring 51, one end of which lies against the side of the pawl and the other end of which is mounted in slot 52 in the end of the pin. The tension of the spring

can thus be adjusted. Such a spring can be employed on the construction shown in Figs. 1-4.

Where a spring is used a foot 53 of leather or other

40 suitable material can be employed between the end of the pawl and the flange member against which it works, the foot being mounted by means of a cotter pin 54

45 extending through holes in the parts. Where the foot is used, the flange, here indicated by 45a, may have a smooth upper surface, friction being relied upon to prevent backward rotation. Also, with this construction,

50 the speed of forward rotation of the tube 14, head 11 and carried parts can be adjusted by adjusting the tension of spring 51.

While I have illustrated preferred forms of my invention, I contemplate another form thereof which comprises the construction shown in Figs. 1-4 without the

55 pawl 42 and flange 45. When the parts 42 and 45 are omitted the member 11 and connected parts progressively rotate counterclockwise. This is due to the fact

that discharge head assembly 24, as it is driven by the reactionary thrust of the issuing liquid, travels faster downwardly than it does upwardly in its rotation about its horizontal axis with the result that, in each cycle of

60 rotation it has a longer time in which to tend to rotate member 11 and connected parts in a counterclockwise direction than in a clockwise direction, the result being the progressive advance of the moving parts counterclockwise about the axis of tube 14.

Although I have shown specific forms of my invention, I contemplate that various changes and modifications can be made without departing from the scope of the invention as indicated by the claims.

I claim:

70 1. In a fluid-distributing device, a body adapted to be attached to a fluid supply conduit, a member rotatably mounted in said body, a fluid discharge head mounted on

said member for rotation about an axis substantially at right angles to the axis of rotation of said member, said head having a discharge nozzle projecting substantially normal to the axis of rotation of the head, and interengaging means on said member and said body preventing relative rotation between said member and body in one direction, said member and body being independently free for relative rotation in an opposite direction.

2. In a fluid-distributing device, a body adapted to be attached to a fluid supply conduit, a member rotatably mounted in said body, a fluid discharge head mounted on said member for rotation about an axis at right angles to the axis of rotation of said member, said head having a discharge nozzle projecting substantially normal to the axis of rotation of the head, and interengaging means on said member and said body preventing relative rotation between said member and body in one direction, said last-mentioned means comprising a pawl on said member and a circular surface on said body engageable by said pawl.

3. In a fluid-distributing device, a body adapted to be attached to a fluid supply conduit, a member rotatably mounted in said body, a fluid discharge head mounted on said member for rotation about an axis at right angles to the axis of rotation of said member, said head having a discharge nozzle projecting substantially normal to the axis of rotation of the head, interengaging means on said member and said body preventing relative rotation between said member and body in one direction, said member and said body being independently free for relative rotation in an opposite direction, and means normally in the path of fluid issuing from said discharge nozzle for, in conjunction with issuing fluid, causing said head to rotate independently of said member.

4. In a fluid-distributing device, a body adapted to be attached to a fluid supply conduit, a member rotatably mounted in said body, a fluid discharge head mounted on said member for rotation about an axis at right angles to the axis of rotation of said member, said head having a discharge nozzle projecting substantially normal to the axis of rotation of the head, interengaging means on said member and said body preventing relative rotation between said member and body in one direction, said last-mentioned means comprising a pawl on said member and a circular surface on said body engageable by said

pawl, and means operated by fluid issuing from said discharge nozzle for causing said head to rotate independently of said member.

5. In a fluid-distributing device, a tubular body adapted to be attached to a fluid supply conduit, a tube rotatably mounted in said body and projecting vertically thereabove, a fitting carried by said tube at the upper end thereof, a hollow horizontally disposed shaft rotatably mounted in said fitting, a discharge head on the end of said shaft, said head having a discharge nozzle projecting substantially at right angles to the axis of rotation of the shaft, means carried by said head and operated by fluid issuing from said discharge nozzle for causing said head and shaft to rotate about the axis of said shaft, a flange on said body having an annular track surface, and a pawl pivoted at one end on said fitting and engageable at its other end with said surface whereby relative rotation of said fitting and said tube in one direction is prevented.

20 6. A device as defined in claim 5 in which a spring is carried by said member and yieldably urges said pawl into engagement with said track.

7. A device as defined in claim 5 in which a non-metallic member is provided between the end of said pawl and said track surface.

8. In a fluid-distributing device, a body adapted to be attached to a fluid supply conduit, a member rotatably carried by said body, a fluid discharge head mounted on said member for free rotation relative to said member about an axis at right angles to the axis of rotation of said member, said head having a discharge nozzle projecting substantially normal to the axis of rotation of the head, and means in the path of fluid issuing from said discharge nozzle for, in conjunction with issuing fluid, causing said head to rotate independently of said member.
